US0D1001873S

(12) **United States Design Patent** (10) **Patent No.:** **US D1,001,873 S**
(45) **Date of Patent:** ** *Oct. 17, 2023

(54) **CAMERA MOUNT**

(71) Applicant: **Zhongshan Forever Photographic Equipment Co. Ltd.**, Zhongshan (CN)

(72) Inventor: **Shenghua Zhang**, Zhongshan (CN)

(73) Assignee: **Zhongshan Forever Photographic Equipment Co. Ltd.**, Zhongshan (CN)

(*) Notice: This patent is subject to a terminal disclaimer.

(**) Term: **15 Years**

(21) Appl. No.: **29/804,314**

(22) Filed: **Aug. 19, 2021**

(30) **Foreign Application Priority Data**

Jul. 8, 2021 (CN) 202130430379.0

(51) **LOC (14) Cl.** **16-05**

(52) **U.S. Cl.**

USPC **D16/237; D16/242**

(57) **CLAIM**

The ornamental design for a camera mount, as shown and described.

DESCRIPTION

FIG. 1 is a top perspective view of a camera mount of the present disclosure;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view of thereof;

FIG. 7 is a top plan view thereof; and,

FIG. 8 is a bottom plan view thereof.

The broken lines shown in the drawings represent portions of the camera mount and form no part of the claimed design.

1 Claim, 8 Drawing Sheets
